UNITED STATES PATENT OFFICE.

HENRY J. HANCOCK, OF NEW YORK, N. Y., ASSIGNOR OF ONE-HALF TO
WILLIAM S. JESSUP, OF NEW YORK, N. Y.

CHAIN-STITCH SEWING-MACHINE.

SPECIFICATION forming part of Letters Patent No. 707,227, dated August 19, 1902.

Application filed December 4, 1901. Serial No. 84,606. (No model.)

To all whom it may concern:

Be it known that I, HENRY J. HANCOCK, a citizen of the United States, residing at New York, in the county and State of New York, 5 have invented certain new and useful Improvements in Chain-Stitch Sewing-Machines, of which the following is a specification.

My invention relates to sewing-machines, and has for its object to provide a sewing- 10 machine for juvenile use that shall be cheap to manufacture, easily operated, and effective in operation.

I attain the objects of my invention by the construction illustrated in the accompanying 15 drawings, in which—

Figure 1 is a side elevation of my improved sewing-machine. Fig. 2 is a front view thereof, the table being in section. Fig. 3 is a view of the two needle-bars in a different position from that shown in Fig. 2. Fig. 4 is a view of the cam-lever in position and a portion of one of the needle-bars. Fig. 5 is an enlarged view of the presser-foot and head carrying the same. Fig. 6 is a view of the 20 central portion of the presser-foot, and Fig. 25 7 is a plan view of the spool-holder.

In the accompanying drawings like numerals of reference refer to the same parts in each of the views, and in the practice of my 30 invention I provide a frame 8, carrying shaft 9, on one end of which I mount a wheel 10, having a handle 11. On the opposite end of the shaft 9 I form a crank-arm 12, on which I mount a cross-bar 13 and one needle-bar 14. 35 On the free end of the bar 13 I mount a second needle-bar 15, which is provided at the lower end with an eye 16, through which the thread 17 passes, and the needle-bar 15 carries an eye-pointed needle 18, while the needle-bar 14 carries a blank needle 19. I also 40 prefer to mount a tension 20 for the thread on the needle-bar 15.

On the frame 8 above the shaft 9 I pivotally mount a cam-lever 21, having a cam-slot 45 22 formed therein, and on the crank 12 I form a shoulder 23, adapted to engage the sides 24 and 25 of said cam-slot 22 and swing the lower end 26 of said cam-lever back and forth, as will be readily understood. In the 50 end 26 of said cam-lever I mount a pin or stud 27, and in the needle-bar 14 I form a lon-

gitudinal slot 28, in which said stud moves, so that the needle-bar 14 is carried back and forth by the movement of the cam-lever 21.

The frame 8 is provided with a cross-head 55 29, in which a presser-foot 30, formed out of a wire rod, is mounted and held in an adjustable manner by set-screws 31. Both ends of the rod forming the presser-foot are mounted in the said head, so that the central portion of the rod forms the part of the presser-foot which comes in contact with the cloth. This part is bent outward, as clearly shown in Fig. 1, and in the central part thereof is formed a slot of peculiar shape, as clearly 60 shown in Fig. 6, one end being substantially V-shaped in form, as shown at 31, the other end having a backwardly-inclined wall 32, and the end is V-shaped in form, as shown at 33, but back or at one side of the end 31, 70 so that when the needles 18 and 19 are at the opposite ends of the slot 34 the needle 19 will be back of the needle 18 and will descend at one side thereof.

Hinged on the frame 8 at 35 is a lever 36, 75 having a downwardly-bent portion 37, in which the needles play, and on the outer end 38 is mounted the cloth plate or table 39, and the lever 36 is controlled by a cam-lever 40, having serrations or teeth 41 on its upper edge, 80 which engage the lower surface of the lever 36 and hold the same at any point in a secure manner, so that the cloth-plate can be raised or lowered, as indicated by dotted lines in Fig. 1, and after the cloth is inserted beneath 85 the presser-foot 30 the cloth-plate is brought up to the presser-foot instead of the presser-foot being lowered on the cloth. I also provide a spool-holder 42, which may be provided with a nut 43 and washers 44, so that tension 90 may be placed on the spool 45, as will be understood, and I also prefer to have a thread-guide 46.

The operation is as follows: The cloth is inserted between the presser-foot and the cloth- 95 plate. The plate is then raised until the cloth will be held rather firm, but not tight enough to prevent the ready feeding of the cloth. The shaft 9 is rotated by the handle 11, and the crank 12 carries around with it the cross-bar 100 13, which is fixed thereon in a predetermined position, and also carries with it the needle-

bar 14, which is pivotally mounted on said crank. The other needle-bar is pivotally mounted on the free end of the cross-bar 13. As the crank 12 is rotated the shoulder 23 5 engages alternately the walls 24 and 25 and carries the needle 19 back and forth in the slot 34 of the presser-foot at the same time the needle-bar is ascending and descending. The parts are so timed that the needle 19 will 10 be in the end 33 of the slot when the needle is descending, at which time it will be at one side of the needle 18, which carries the thread, and as the needle 19 descends the needle 18 is timed so that it will commence its ascent 15 and throw out a loop 47, through which the needle 19 passes in its descent. When the needle 19 is at the lowest point, it will be carried toward the other needle by reason of the shoulder 23 engaging the side 25 of the cam 20 until both needles are at the end 31 of the slot, as clearly shown in Fig. 3, at which time the needles are substantially in the same line, and the needle 18 is held in the end 31 during its descent, so that it must pass directly 25 through the loop of the thread held on the needle 19, and the needle 19 is so timed that it will leave the loop shortly after the needle 18 enters it and is ready to descend again and catch the next loop as it is thrown out. At 30 the time the needle 19 is brought forward to hold the needle 18 in the end of the slot 34 it will feed the cloth along the length of the stitch, as will be readily understood. The inclined end 32 of the slot 34 serves to carry the 35 needle 19 back, so that it will pass on one side of the needle 18 in the descent and pass through the loop of the thread instead of striking against the needle 18; but when the needle 19 passes out from this end of the slot 40 it immediately springs back into a line parallel with the needle 18, this being effected by the looseness and spring of the parts; but the parts are held quite rigid by the V-shaped end 31 of the slot 34 and the cam-lever 21 45 when the needle 18 is descending, so that the needle 18 cannot fail to pass through the loop held on the needle 19, this part not being illustrated because it will be readily understood by any one skilled in the art.

50 It will be understood that many changes in the details of construction can be made without departing from the spirit of my invention, and I reserve the right to make all such changes.

55 Having thus described my invention, what I claim as new, and desire to secure by Letters Patent, is—

1. A chain-stitch sewing-machine comprising a frame, a crank-shaft provided at one end with a crank, means to rotate said shaft, two needle-bars carrying needles mounted on

said crank, a cam-lever positively operated by said crank and controlling one of said needle-bars, a cloth-plate, and a presser-foot provided with a slot adapted to carry one needle 65 back, or at one side of the other in its descent, and to hold the needles parallel during the descent of the other needle, for the purpose set forth.

2. A chain-stitch sewing-machine comprising 70 a frame, a crank-shaft provided at one end with a crank, means to rotate said shaft, two needle-bars carrying needles mounted on said crank, a cam-lever pivotally connected with the frame above said shaft and provided 75 with a slot, said crank being provided with a projection in engagement with the walls of said slot in the cam-lever, said cam-lever being in engagement with one of said needle-bars, a cloth-plate, and a presser provided 80 with a slot adapted to carry one needle back, or at one side of the other in its descent, and to hold the needles parallel during the descent of the other needle, as and for the purpose set forth. 85

3. A chain-stitch sewing-machine comprising 90 a frame, a crank-shaft provided with a crank and means to rotate said shaft, a cross-bar fixed on said crank, a needle-bar pivotally mounted on said crank, a second needle-bar pivotally mounted on the free end of said cross-bar and carrying an eye-pointed needle, a presser-foot provided with a slot adapted 95 to carry the respective needle back of the eye-pointed needle during its descent and to hold the needles parallel during the descent of the eye-pointed needle, a cam-lever mounted on the frame and provided with a cam-slot and a stud engaging a slot in one of said needle-bars, and a shoulder on said crank adapted 100 to engage said cam-lever to positively control said needle-bars, as and for the purpose set forth.

4. A chain-stitch sewing-machine comprising 105 a frame, a crank-shaft provided with a crank having a shoulder, two needle-bars mounted on said crank, a cam-lever adapted to positively control said needle-bars, a presser-foot provided with a slot adapted to control the movement of the needles during a portion 110 of their movement, a lever pivoted on the frame, a cloth-plate mounted thereon, and a cam-lever provided with serrations or teeth adapted to engage said last-named lever, as and for the purpose set forth. 115

In testimony whereof I have signed my name to this specification in the presence of two subscribing witnesses.

HENRY J. HANCOCK.
